SAFETY RAZOR

George Taylor, Penwortham, Preston, England

Application June 11, 1932, Serial No. 616,715, and
in Great Britain September 22, 1931

10 Claims. (Cl. 30—12)

This invention relates to a safety razor having a reciprocating blade carrier to which the blade is secured by means of a backing plate, the invention being particularly concerned with the means 5 by which the backing plate is secured to the razor.

The object of the invention is to provide a simple means of attaching the backing plate with the blade beneath it so as to secure ready 10 attachment for cleaning or replacement.

The features of the present invention will be better understood from the accompanying drawing which illustrates one form of the invention:

Fig. 1 is a side elevation showing the complete 15 razor with a reciprocating blade;

Fig. 2 is a plan view of Fig. 1 with the blade, cover plate and part of the blade carrier removed;

Fig. 3 is a sectional view of Fig. 2 on the line 20 A—A with blade and cover plate in position;

Fig. 4 is a sectional view taken on the line B—B of Fig. 3.

Referring to Figs. 1, 2, 3 and 4, 1 is a handle connected with a bridge piece 2; the two end plates 3 and 4, support the carrier 5 by means 25 of projecting pins 6, 7; the carrier also has the pin 8 working in the cam groove 9 of the roller 10, while 11 is a guard roller for preventing injury from the inoperative side of the blade 12; 13 is a backing plate provided with a stem 14 near 30 the end of which shoulders are provided formed by a circumferential groove 15, while the carrier has the central hole 16 into which the stem 14 is passed so that the groove 15 projects beneath the carrier 5.

Mounted on the carrier by the screws 17 is the locking plate 18 provided with an extension 18a which projects outside of the razor frame by passing through and beyond the end plate 4 so that it can always be engaged irrespective of where 40 the carrier stops during its reciprocation, the extension being of rectangular cross section and working in a rectangular hole in the end plate 4, so that limitation of the tilting of the carrier 5 is obtained. The locking plate 18 is provided 45 with springs 19 working in slots of the plate against the abutment pins 17, while the central hole 20 surrounds the groove 15 of the stem 16, the normal position of the springs 19 being such as to push the edge of the locking plate into the 50 groove 15 when the backing plate is in position.

The end of the stem 14 is provided with cam surfaces 14a which as the stem is pushed into place, engage with the edge of the hole 20 so as to cause the locking plate to move automatically 55 against the pressure of the springs 19 until the groove 15 coincides with the hole 20, whereupon the locking plate shoots to the right to engage the groove.

The blade 12 is bent owing to the pressure of 60 the backing plate 13 being pushed into place far

enough for the groove 15 to engage the locking plate 18. Consequently on being released, owing to pressure on the end 18a of the locking plate as shown in Fig. 2, the tendency of the backing plate is to be shot out of engagement owing to the 65 straightening out of the blade 12 upon release from its fixing.

It will be noted that when the razor is being assembled into the position shown in Fig. 4, the double edged blade 12 guides itself on the periphery of the end plates 3 and 4, so as to acquire the necessary set without any appreciable friction on the moving parts.

From the preceding description it will be seen that a single pressure on the locking plate direct 75 suffices to immediately release the blade from its holder, and a similar pressure on the backing plate returns it to place. Consequently, replacement, or removal for cleaning, is attained very 80 quickly and by means of a device so simple that it is not likely to get out of order.

It will be understood that the invention is not limited to the form shown but only in so far as defined by the appended claims.

What I claim is:—

1. In a safety razor including a razor frame, a reciprocating blade carrier moving between end plates on the razor frame, the combination with a backing plate including a stem adapted to pass 90 through the carrier for securing the blade thereto, of shoulders on the said stem and a spring pressed locking plate slidably mounted on and under the said carrier to move parallel therewith, for engaging the said shoulders, and an 95 extension on the said locking plate, projecting through and beyond one of the said end plates to permit of the locking plate being released from the said shoulders irrespective of where the carrier stops during its reciprocation.

2. In a safety razor including a razor frame a reciprocating blade carrier moving between end plates on the razor frame, the combination with a backing plate including a stem adapted to pass 100 through the carrier for securing the blade thereto, of shoulders on the said stem formed by a circumferential groove in the said stem and a spring pressed locking plate slidably mounted on and under the carrier to move parallel therewith and apertured to receive the said stem, cam

means on the said stem for engaging the aperture on the said plate so as to cause the locking plate to move and automatically engage the said groove under the spring action, means normally holding the locking plate in position 110 against the spring action for the aperture to receive the said cam means, and an extension on the said locking plate, projecting through and beyond one of the said end plates to permit of the locking plate being released from the said 115 120

shoulders irrespective of where the carrier stops during its reciprocation.

3. In a safety razor including a razor frame, a reciprocating blade carrier moving between end plates on the razor frame, the combination with a backing plate including a stem adapted to pass through the carrier for securing the blade thereto, of shoulders on the said stem and a spring pressed locking plate slidably mounted on and under the carrier to move parallel therewith for engaging the said shoulders and an extension of rectangular cross section on the said plate projecting through and beyond one of the said end plates to limit the rocking movement of the carrier and to permit of the locking plate being released from the said shoulders irrespective of where the carrier stops during its reciprocation.
4. In a safety razor including a reciprocating blade carrier and a frame supporting the carrier, the combination with a backing plate including a stem adapted to pass through the carrier for securing the blade thereto, of shoulders on the said stem formed by a circumferential groove in the said stem, a locking plate slidably mounted on the carrier to move parallel therewith and apertured to receive the said stem, spring means between the carrier and the locking plate urging the locking plate into a position to engage the said groove, cam means on the said stem for engaging the aperture in the said plate, so as to cause the locking plate to move and automatically engage the said groove under the spring action, and an extension on the locking plate projecting outside of the said frame to permit of the locking plate being released from the shoulders irrespective of where the carrier stops during its reciprocation.

5. In a safety razor including a razor frame comprising end plates connected by a bridge piece for attachment to a handle, and a reciprocating blade carrier mounted to move between the end plates, the combination with a backing plate including a stem adapted to pass through the carrier for securing the blade thereto, of shoulders on the stem formed by a circumferential groove in the stem, a slideable locking plate apertured to receive the said stem, abutment pins on the underneath of the carrier engaging in slots in the locking plate, springs housed in the said slots between the abutment pins and the ends of the slots so as to urge the opposite ends of the slots into engagement with the abutment pins, cam surfaces on the ends of the said stem for engaging the said aperture so as to cause the locking plate to move and automatically engage the said groove under the spring action, and an extension on the locking plate projecting outside of the razor frame to permit of the locking plate being released from the shoulders irrespective of where the carrier stops during its reciprocation.

6. In a safety razor including a razor frame comprising end plates connected by a bridge piece for attachment to a handle, and a reciprocating blade carrier mounted in and to move between the end plates, the combination with a backing plate including a stem adapted to pass through the carrier for securing the blade thereto, of shoulders on the stem formed by a circumferential groove in the stem, a slideable locking plate apertured to receive the said stem, abutment pins on the underneath of the carrier engaging in slots in the locking plate, springs housed in the said slots between the abutment pins and ends of the slots so as to urge the oppo-

site ends of the slots into engagement with the abutment pins, cam surfaces on the ends of the said stem for engaging said aperture so as to cause the locking plate to move and automatically engage the said groove under the spring action, and an extension on the locking plate projecting through and beyond one of the end plates to permit of the locking plate being released from the shoulders irrespective of where the carrier stops during its reciprocation.

7. In a safety razor, the combination of a razor frame including end plates, the upper peripheries of which are curved convexly, a reciprocating blade carrier mounted to move between the end plates, a curved backing plate including a stem adapted to pass through the carrier for securing the blade thereto, the carrier and the backing plate being so shaped as to bend the blade substantially to the curve of the end plates, whereby the blade is guided by the end plates and tensioned, shoulders on the stem of the backing plate, a spring pressed locking plate slidably mounted on the carrier for engaging the said shoulders, and an extension on the locking plate, projecting outside of the razor frame to permit of the locking plate being released from its shoulders, irrespective of where the carrier stops during its reciprocation, whereby the tensioned blade may be automatically shot off the carrier.

8. In a safety razor, the combination of a razor frame including end plates, the upper peripheries of which are curved convexly, a reciprocating blade carrier mounted to move between the end plates, a curved backing plate including a stem adapted to pass through the carrier for securing the blade thereto, the carrier and the backing plate being so shaped as to bend the blade substantially to the curve of the end plates, whereby the blade is guided by the end plates and tensioned, shoulders on the stem of the backing plate, formed by a circumferential groove in the said stem, a locking plate slidably mounted on the carrier to move parallel therewith and apertured to receive the said stem, spring means between the carrier and the locking plate urging the locking plate into a position to engage the said groove, cam means on the said stem for engaging the aperture in the said locking plate, and an extension on the locking plate projecting outside of the razor frame to permit of the locking plate being released from its shoulders, whereby the tensioned blade may be automatically shot off the carrier.

9. In the structure according to claim 5, curving the upper peripheries of the end plates convexly and shaping the carrier and the backing plate so as to bend the blade substantially to the curve of the end plates, whereby the blade is guided by the end plates and tensioned so as to shoot off the carrier when the locking plate is released.

10. In a safety razor including a frame with end plates attached to a handle by a bridge piece, a reciprocating blade carrier mounted centrally of and moving between the said end plates, a backing plate including a stem passing centrally through the carrier, a locking plate for the blade mounted to reciprocate on the said carrier against the action of a spring and co-operating with the stem to secure the blade on the carrier, and an extension on the locking plate projecting outside the said frame.

GEORGE TAYLOR.
